UNITED STATES PATENT OFFICE.

ERNEST B. PRIEBE, OF INWOOD, NEW YORK, ASSIGNOR OF ONE-HALF TO WARREN C. DRAKE, OF INWOOD, NEW YORK.

FURNACE-GRAVE.

1,360,250.

Specification of Letters Patent. Patented Nov. 23, 1920.

Application filed July 28, 1919. Serial No. 313,590.

To all whom it may concern:

Be it known that I, ERNEST B. PRIEBE, a citizen of the United States, residing at Inwood, Long Island, in the county of Nassau and State of New York, have invented a new and useful Furnace-Grate, of which the following is a specification, reference being had therein to the accompanying drawing.

10 This invention relates to furnace grates and more particularly to the twyer construction, forming the fuel bed support of a furnace and supplying air of combustion to the fuel.

15 The main objects of the invention are to afford a furnace grate construction which will have greater efficiency in regard to its air supplying function and otherwise, greater durability with reduced liability to damage, ease of removal and replacement of injured or destroyed members, and economy and low cost of construction. A further object is to enable the principles of the present invention to be applied to the standard 20 makes of furnace or stoker construction, and the same are applicable to various types, for example, the stationary grate, the reciprocating grate, or the traveling grate. In the well known Taylor stoker, the main 25 portions of the grate are stationary although certain portions are reciprocatory; and for convenience of illustration I have adopted some of the general features of the Taylor stoker and incorporated therewith the features of the present improvement.

30 To the attainment of the above mentioned objects, the present invention consists in the novel furnace grate and the novel features of construction, combination, arrangement, mechanism and detail herein illustrated, described or claimed.

35 In the accompanying drawings, Figure 1 is a general side elevation of the interior parts of a furnace of the Taylor type but modified to incorporate the present invention.

40 Fig. 2 is a similar side elevation on a larger scale, of the particular parts to which the invention pertains, and broken away in certain respects for purposes of illustration.

45 Fig. 3 is a perspective view of one of the grate members, which may be termed a grate bar or a twyer plate, constructed in accordance with the present invention.

50 Fig. 4 is a top view of several adjacent

twyer members in face contact, seen from direction of arrow 4 in Fig. 2.

Fig. 5 is a transverse section of one of the interlocking cap plates overlying the twyer plates.

Fig. 6 is a transverse section of the grate as a whole, taken approximately on the line 6-6 of Fig. 1.

Figs. 7 and 8, in transverse section, show a modification of the structure and mounting of the twyer plates and cap plates.

The drawings show the usual front wall 10, and at the rear a bridge wall 11. The side walls 12 may be of the usual construction.

At the front, exterior to the furnace, is the fuel hopper 14, beneath which is the reciprocating infeeding ram or pusher 15. This thrusts the fuel rearwardly into the furnace where it forms and maintains a bed 16, indicated both in Fig. 1 and Fig. 6. The fuel from the ram case passes through the throat or beneath the front wall 10 and thence into a series of retorts 17. These retorts are in the form of inclined troughs extending downwardly toward the rear of the furnace. In each retort is one or more distributing rams 18 which maintain the fuel in gradual progress downward and toward the rear.

70 The retorts are formed between structures that may be termed twyer boxes 19, as seen in Fig. 6, and above each twyer box is a series or bank 20 of the twyer members or blocks 30, giving a construction whereby 75 air is furnished into the heart of the burning fuel bed as it progresses rearwardly. Fig. 1 shows a wind box 22 having compartments leading, respectively, to the twyer boxes and to an extra or a terminal grate section 23 located to the rear of the twyer boxes. The fuel traveling down over the inclined structures described, passes from the terminal grate section 23 to an automatic dumping mechanism 24 of usual construction. The grate section 23 may be reciprocated by connecting rod 25 extending to the front of the apparatus.

80 In the Taylor structure, the twyer construction on top of the twyer box, is built 85 up of a certain form of twyer plates laid horizontally in step fashion, with certain provision for air passages so that the forced draft through the twyer box and wind box 90 will supply air to the interior of the burn- 95

ing fuel. This mode of construction, and that in various other makes of stoker, is far from satisfactory, and the present invention purports to afford a construction improved 5 in the respects herein enumerated.

The twyer members 30 hereof, which are solid structures and may be termed blocks, are shown formed, constructed, and arranged, in a certain novel manner. The 10 several blocks are set not horizontally, as in the prior structure, but substantially each block is upstanding or outstanding from the box; its weight rests upon the box, forming an underneath support for it. The twyer 15 blocks are herein stacked in mutual contact, face to face, each one in its length upstanding from the supporting box beneath. For the purpose of definition, to make clear the present improvement, I shall term the 20 length of each twyer block the distance a to b on Figs. 2. and 3. The distance a to c is the thickness. The distance d to e is the 25 width, corresponding to the width of the twyer box below. In this invention, the length and the height of the block are substantially the same thing. Its length does not lie horizontal, as in the prior structure, but the outer end or that removed from the 30 box is substantially higher than the inner end, where it rests upon the box.

The twyer block hereof, while preferably made in one piece, as in Figs. 3 and 6, may be made in two pieces, as in Figs. 7 and 8, although in the latter case they will be substantially rigidly united in use. In either 35 form, the twyer member or block, as a whole, is hollow for the free flow of air from the box to the twyers or passages. In both forms, each block comprises a pair of opposite, upstanding, substantially longitudinal side bars 31. These preferably converge, as shown, and instead of meeting above are somewhat too short to meet, each bar having a top side 32 engaging the cap plates to 40 be described.

In the main form, Figs. 3 and 6, the twyer block has a thin cross connector or web 33 integral with the side bars and rendering the entire block a unitary structure. The 45 web is shown as having a positioning extension 34 projecting downwardly to engage the walls of the twyer box, as shown. Each web is perforated with a hole 35 to receive a bolt serving to secure together the entire stack of blocks.

What I term the face 36 of each twyer block, and of each of the side bars 31 thereof, is the plane or surface which stands in face contact with the similar plane or surface of the adjacent twyer block. One way to define the position of the twyer members hereof is to state that the faces or the planes of face contact between the successive members is upstanding, or substantially at right angles to the top edges of

the twyer box which gives support to each separate twyer member. This structure has numerous advantages not only in operation but for the purposes of removal and replacement, and also in manufacture or construction. These advantages will appear from the description herein or will be apparent to those skilled in the art. 70

The described structure and arrangement permits laterally directed twyer openings to 75 be readily supplied. Thus, each of the faces 36 of each of the blocks may be provided with grooves or passages. I am enabled, for example, to cast a half round groove on the face of one block, and a corresponding half round groove on the opposite face of the adjacent block, the two registering as shown, to give a round aperture or twyer. As shown in the cross sections, each of these is tapered, affording a nozzle which directs 80 the air with suitable force, laterally into the advancing bed of fuel in each of the retorts 17. Three of such twyer passages are shown between each pair of blocks; the lowest passage, 37, being of quite large diameter, and those above, 38 and 39, being of progressively smaller size. By this, the air is caused most effectively to reach into the heart of the fuel bed passing along the retorts. Owing to the advantageous converging 85 shape of the blocks, as seen in Fig. 5, the lower and larger twyer openings, 37, have their outlets nearer to the center of the retorts and they deliver air with the greatest force, below the zone of fire. 90

The twyer blocks may be secured in their relative position and drawn forcibly into face contact by a long bolt 41 passing through the holes 35 in the webs of the respective blocks. This construction affords a 105 wholly rigid twyer system supported firmly on the top of the air supplying twyer box. 100

For some purposes it might be desirable to form each twyer member as two separate bars 31^a, 31^a, as shown in Figs. 7 and 8, in 110 which case a longitudinal supporting channel 43 may be supplied over which the web 33^a of each bar lies. Each web having the same perforation 35^a, as before, the securing bolt 41 may be employed, and extending 115 downwardly from this bolt at suitable points may be tie bars 44 extending and secured beneath cross bars 45.

The twyer member hereof, with its converging side bar arrangement, the tops of 120 the two bars 31 approaching but not meeting, permits a series of cap pieces or plates 50 to be applied and firmly secured by being dovetailed below the top extremities of the bars. These cap pieces are shown in 125 cross section in Fig. 5, and each may be of sufficient length to extend over four or more twyer members, as indicated in Figs. 1 and 2. Each cap piece 50 has an arched body resting directly on the tops of the twyer 130

bars, and one or more depending dovetail extensions 51 by which the plate is locked in place. Each cap piece is also shown as overlapping the next lower one in the series, and as having exterior ribs one of which, 52, serves for relatively positioning and locking each cap piece to the next one below. Each cap piece, additionally, has lateral passages or twyer openings 53.

10 Thus, a very effective and uniform air distribution is afforded throughout the fuel bed. It may be advantageous to furnish a certain amount of air in an upward rather than a lateral direction, and I have therefore shown the lower extremity or nose 54 of each cap piece standing directly above a dip or recess 55 at the top side of the next lower cap piece, thus permitting the air to pass out at the top, as indicated in Fig. 2.

15 Remaining to be described are special terminal blocks 60 above the topmost of the series or stack of twyer members and members 61 below the same. The blocks 60 may have face grooves to correspond with those in the first of the twyer members 30, as seen in Fig. 2. It may also have a rib 62 for positioning and maintaining packed asbestos at this point of the stoker. There may be a special cap piece 63 which overlies the first 20 regular cap piece 50 and is held firmly in place by a bolt 64. The lowermost terminal block 61 may have an underlying foot 65 for locking it in place.

25 The operation of the present invention so far as concerns the replacement of injured or burned out twyer members or cap plates, may be simply as follows: Loosening the bolt 64 permits the special topmost cap plate 63 to be displaced, and when this is

30 done the way is opened to displace and remove any one or all of the cap plates. A slight upward adjustment of any cap plate removes its locking rib 52 from beneath the adjoining end of the next lower plate. Thus, 35 any injured cap plate can be swung around until its locking extension 51 stands longitudinally permitting the cap plate to be quickly taken out and replaced. This also gives access to the stacked twyer members.

40 Being placed substantially upright, with their weight resting on the twyer box, the plates are practically independent of each other, and, when the connecting bolt 41 is loosened or removed, any defective twyer 45 member may be lifted out of place and replaced by a new one by simply loosening and moving slightly up the incline the twyer members above it.

46 The form of the twyer members, which converge from their base upwardly, giving an inverted V-shape or rather an A-shape, is advantageous. Instead of stating that the members converge upwardly, they may be described as diverging downwardly, and 50 this arrangement gives a shape of retort

which is wider above and converges downwardly. The portion of the fuel bed to which the air is fed widens out from the base upwardly and, as shown in Fig. 6, the top line of the fuel bed, considered transversely, 55 should be or may be substantially horizontal. The diverging sides of the upper part of the retort afford air feeding nozzles or apertures 37, 38, 39 and 53, which are in stepped relation, as already explained, so that the 60 burning body of fuel is most effectively supplied with air of combustion. To illustrate this, I have applied a series of arrows at the right hand retort in Fig. 6, to indicate or suggest generally the manner of air flow 65 from the twyer apertures into the fuel bed.

70 In this connection, I find it advantageous to construct the twyer superstructure at the extreme sides of the furnace of somewhat greater height than the intermediate ones. 75 Fig. 6, at the sides, illustrates this. Special asymmetrical twyer members and cap plates are provided for the extreme sides of the furnace, as shown, which need no special 80 additional description, and in manufacturing these I design them of greater length or height. The greater tallness of the edge members conduces to a greater efficiency of combustion. At the same time it enables forming one additional twyer opening at 85 the face of each member, so that we have four instead of three graded discharge nozzles delivering air into the retorts. Above these four are the discharge apertures 53 formed at the base of the cap plates, and 90 above these the upward air outlet formed between the successive cap plates, as already described.

95 Both at the edge twyer structures and the intermediate ones we, therefore, have 100 graded twyer discharges laterally into the fuel bed in the retorts, and thereabove the upwardly directed discharge, not into the retort but directly toward the top of the fire bed.

105 Instead of having the two opposite side bars of each twyer member arranged in direct alinement, with their faces in the same planes, I prefer to symmetrically slant them, as seen in the top view, Fig. 4, so that 110 they nest or fit together as shown, and so that the laterally directed air jets have an incline or slant slightly in the direction of the gradual advancing travel of the fuel bed, that is toward the rear or bridge wall 115 of the furnace.

120 The perspective Fig. 3 is provided with construction lines to assist understanding the structure. The rectangular solid indicated by the outer construction lines is supposed to stand vertically on edge with its base plane horizontal. Its upper edges *fghi* are horizontal, and *fg* passes through the metal corners *j, k* of the surfaces 32. The lower edge *lm* is horizontal. Directly above 125

it is a horizontal line *no*, which touches metal corners *n, o*. The line *de* is above the base plane and beyond the plane *fgml*. The point *b*, beneath *a*, is in the base plane. The bottoms of the lugs *34* are in the base plane. The metal corners *a, p* are above the plane *fghi*, and are beyond the plane *fgml* on account of the incline of the side bars *31*. The metal corners *c, q* are higher than *a, p*. 5

10 The verticals below *g* and *h* pass through corners *o* and *r*, but the metal corners *s, t* are beyond the plane *ihr*. These details are merely the disclosure of one mode of embodying the improvement.

15 It will thus be seen that I have described a furnace grate embodying the principles and attaining the objects and advantages of the present invention. Since many matters of combination, arrangement, design and detail 20 may be variously modified without departing from the underlying principles, no limitation to such matters is intended except in so far as set forth in the appended claims.

What is claimed is:

25 1. A furnace grate comprising retorts separated by air boxes, and above each air box a bank of outstanding hollow twyer members, each member consisting of two opposite spaced-apart bars connected by a 30 thinner web.

35 2. Structure as in claim 1 and wherein the opposite bars, converging upwardly, leave a space, and a series of cap plates overlying the bank of twyer members and engaging in the space between the opposite bars thereof.

3. Structure as in claim 2 and wherein each cap plate has a locking extension which may be inserted between the opposite bars and swung into locking position.

40 4. A furnace grate comprising retorts separated by air boxes, and above each air box a bank of outstanding hollow twyer members, each member consisting of spaced apart bars, and overlying said members a 45 series of overlapping cap plates.

5. Structure as in claim 4 and wherein each cap plate locks with the overlapping and underlapping cap plates and with the twyer members beneath.

50 6. Structure as in claim 5 and wherein the means locking the cap plates with the twyer members is a thin dovetail extension on each cap plate, unlocked and locked by swinging the cap plate when disassembling or assem-

55 bling.

7. Structure as in claim 4 and wherein the spaced-apart bars of each twyer member are arranged at symmetrically slanting angles to the direction of fuel advance, namely, slanting toward the furnace rear. 60

8. Structure as in claim 7 and wherein air orifices are directed through said bank of members into the fuel at a similar slanting angle.

9. A furnace grate comprising an air box, 65 and a bank of outstanding hollow twyer members thereon, the same formed to provide air passages directed laterally into the fuel bed, said passages being of graduated sizes and the larger being lower and having 70 orifices slanted toward the furnace rear.

10. A furnace grate comprising an air box, and a bank of outstanding hollow twyer members thereupon, formed to provide air 75 passages directed laterally into the fuel bed, such air passages having their orifices directed slantingly toward the furnace rear and being at different levels, with the lower passages of larger orifice than the higher ones. 80

11. A twyer member having the shape of the letter A with the tops of the side bars spaced apart and the cross web thinner than the side bars.

12. Twyer member as in claim 11 and 85 wherein each side bar has grooves forming air passages directed into the fuel bed.

13. In a furnace grate a bank of upstanding hollow twyer blocks stacked in face contact, each consisting of two opposite side 90 bars spaced apart, and a series of cap plates locking with the tops of said bars, each having underneath grooves affording lateral twyer apertures.

14. In a furnace grate a bank of upstanding hollow twyer blocks stacked in face contact, each consisting of two opposite side bars spaced apart, and a series of cap plates locking with the tops of said bars, each having underneath grooves affording lateral 110 twyer apertures, and upward orifices.

15. In a furnace grate a bank of upstanding hollow twyer blocks stacked in face contact with lateral orifices directed into the fuel bed, each block having its sides symmetrically inclined toward the furnace rear, and said orifices being similarly inclined. 105

In testimony whereof I have affixed my signature hereto.

ERNEST B. PRIEBE.
